DISPLAY CASE FOR SAFETY RAZOR AND BLADES

Charles L. Metzler, 14 Overlook Road, Alpine, N.J., John D. Wark, 326 W. Lena Ave., Freeport, N.Y., and Leon B. Bernstein, 31 Jefferson Ave., Hicksville, N.Y.

Filed Jan. 18, 1962, Ser. No. 68,366

Term of patent 14 years

(Cl. D58—12.6)

FIG. 1 is a top perspective view of a display case for safety razor and blades, in closed position, showing our new design; and

FIG. 2 is a top perspective view thereof in open position.

The cover is represented as having a central projecting section of triangular cross section and flat end areas stippled to indicate a pebbled surface texture. The bottom or tray portion of the case is represented as having downwardly converging portions presenting transverse corrugations of ornamental character and recesses shaped to receive a razor head and blades, not shown.

The present application is a continuation-in-part of our pending application Serial No. D. 64,472, filed March 24, 1961, now abandoned.

The rear and side of the case not shown are substantially plain.

We claim:

The ornamental design for a display case for safety razor and blades, substantially as shown and described.
